PREFABRICATED CORNICE FOR ROOF CONSTRUCTION

Joseph R. Duncan, P.O. Box 693, Abilene, Tex. 79604
 Filed July 13, 1964, Ser. No. 382,243
 8 Claims. (Cl. 52—92)

This invention relates to building structures and more particularly to a cornice.

In the construction of wood frame buildings such as residences, etc. the cornice installation is a slow, time consuming task.

An object of this invention is to provide a block for the installation of cornices.

Another object is to provide such a block wherein the crooked rafters are readily straightened and smooth, even cornices are quickly installed.

A further object is to provide a block for installing cornices on brick veneer buildings also providing for the brick pocket, i.e. a facer board over the top of the brick.

Still further objects are to achieve the above with a device that is sturdy, compact, durable, simple, and reliable yet inexpensive and easy to manufacture and install.

The specific nature of the invention as well as other objects, uses, and advantages thereof will clearly appear from the following description and from the accompanying drawing, the different views of which are not necessarily to the same scale, in which:

FIG. 1 is a sectional view of a building illustrating an embodiment of this invention.

FIG. 2 is a sectional view of a building illustrating a second embodiment of this invention.

FIG. 3 is a perspective view of the block shown in FIG. 1.

FIG. 4 is a schematic representation of the frame of a building utilizing this invention with parts broken away and in section for better illustration of the invention.

Referring more particularly to FIG. 1, there is represented a frame building with a brick veneer 10. The structure includes wall studs 12 which form a portion of the wood frame of the walls and the studs have wall plate 14 on top thereof. Insulating board 16 is attached to the outside of the wall studs 12. The roof frame 18 (seen in full in FIG. 4) includes ridge pole 19, wood rafters 20, and tie beams 21.

This invention is particularly concerned with block 22 (FIGS. 1 and 3) by which the cornice comprising the soffit 24, facia 26, and facer board 28, are applied.

The block 22 includes the horizontal soffit support 30 which is beveled on its outer edge at 31 to fit the rafter 20. The horizontal soffit support 30 is attached by two first scabs 32 to vertical wall member 34. The vertical wall member 34 has notch 36 therein to fit over stringer 38 as will be explained later. Two second scabs 40 on either side of the block 22 attach to the soffit support 30 to the rafters. Two third scabs 42 are attached to the vertical wall member 34 and extend upward therefrom and are stapled to the rafter 20. The scabs are made of plywood and attached by stapling.

In describing the use of the block 22 for cornicing the structure, first, the stringer 38 is attached to the wall frames on the outside of the insulating board 16. As may be seen more particularly in FIG. 4, some of the rafters are not aligned with studs 12 and therefore, the block 22 will be attached only to the rafter and the attachment of the toenailing into the stringer 38. Any crooked rafters are cut partially through as at 44. This permits the rafter end to be aligned by the block 22. Then the vertical members 34 are beveled at top and the top fits about one half inch below the rafter to compensate for irregularities. The cornice blocks 22 are attached to

2

the rafters 20 by stapling through the scabs 40 and 42. After the blocks are attached, the soffit 24 is attached to the underside of the soffit support 30 and the facia 26 is attached to the end of the rafters 20. The facia 26 has a longitudinal notch and the soffit 24 fits within the notch of the facia. After the soffit is attached, the facer board 28 is attached to one face of the vertical wall member 34 forming the brick pocket. The facer board is attached after the soffit and therefore, the facer board butts against one edge of the soffit to hold it securely in place. It may be seen that there is a brick pocket formed behind the facer board 28 so that the brick 10 may be laid up behind the facer board.

Also it may be seen that the block 22 is adaptable for forming cornices on "eyebrow" eaves 45, i.e. eaves that are formed upon a gable at a level even with the eaves formed at the side of the structure. Such an application is shown of the right hand side of FIG. 4. A false rafter 46 is scabbed to the side of the gable studs by means of the block 22, facia 26, and soffit 24 and facer board 28 attached to this as though it were a regular eave.

Referring more particularly to the embodiment shown in FIG. 2, it may be seen there is also provided a block 50 adaptable for a frame house which has siding thereon. In this case, the soffit support 52 is attached to the vertical wall member 54 by two first scabs 56 which also extend upward forming a scab to attach the block to the rafter 22. Two second scabs 58 on each side of the block 50 attach the soffit support 52 to the rafter 20. The installation of the block 50 is quite similar to the installation of the block 22; i.e. after the rafters 20 have been attached, the blocks 50 are attached to the rafters by stapling and the soffit 24 and facia 26 installed. In this case, the top siding member 60 butts against the edge 35 of the soffit 24 to finish the installation.

Of course, it will be understood that FIG. 3 illustrates a block which would be sold as a separate item in commerce and which would be prepared at a central shop and sent to the job to be installed as a unit. Therefore, it may be seen that I have provided a particularly quick and simple method to attach cornices which will be smooth, even, and sturdy.

The top of the notch 36 is on a level line with the bottom of the soffit support 30. Therefore a chalk line may be made on the insulation 16 which is level with the tail end of the rafter 20. Then the stringer 38 is attached with its top level with the chalk line. Therefore attachment of the block 22 with the notch 36 on the stringer 38 will result in a smooth even cornice.

It will be apparent that the embodiments shown are only exemplary and that various modifications can be made in construction, materials, and arrangement within the scope of the invention as defined in the appended claims.

55 I claim as my invention:

1. In a building structure having
  - (a) walls,
  - (b) a roof frame on the walls with
  - (c) wood rafters which
  - (d) extend over the walls to form eaves, and
  - (e) a facia attached to the ends of the rafters; the improved cornice comprising in combination:
- (f) a plurality of composite blocks, each having
  - (i) a vertical wall member and
  - (ii) a horizontal soffit support,
  - (iii) at least one first scab attaching the vertical wall member and horizontal soffit support together,
  - (iv) at least one second scab attaching the horizontal soffit support to the eave portion of one of the rafters,

- (g) one of said composite blocks so attached to each rafter, and
  - (h) a soffit attached to the underside of the soffit supports.
2. The invention as defined in claim 1 wherein
- (j) said soffit is fitted within a horizontal notch in the facia.
3. The invention as defined in claim 1 wherein
- (j) said first scab also extends upward and is also attached to the eave portion of one of the rafters. 10
4. The invention as defined in claim 1 with the addition of
- (j) at least one third scab attaching the vertical wall member to the eave portion of the rafter.
5. The invention as defined in claim 4 wherein
- (k) the lower portion of the vertical wall member extends below the bottom of the soffit and
  - (m) a facer board is attached to the lower portion of the vertical wall member, thus forming a brick pocket.
6. In a building structure having
- (a) wood frame walls,
  - (b) a brick veneer over the walls,
  - (c) a roof frame on the walls with
  - (d) wood rafters which
  - (e) extend over the walls to form eaves,
  - (f) a facia attached to the ends of the rafters,
  - (g) a soffit, and
  - (h) a facer board extending from the soffit to below the top of the brick;
- the improvement comprising:
- (j) a stringer attached to the wood frame walls above the brick veneer and below the rafters,
  - (k) a composite block attached to each rafter having
- (i) a horizontal soffit support,
  - (ii) a vertical wall member,
  - (iii) first scabs on each side of the block attaching the soffit support to the wall member,
  - (iv) second scabs on each side of the block attaching the soffit support to the eave portion of the rafters,
  - (v) third scabs on each side of the block attaching the wall member to the eave portion of the rafter,
  - (vi) a notch in the vertical wall member fitted to the stringer;
- (m) said soffit attached to the underside of the soffit support, and
- (n) said facer board attached to the wall member.
7. In a building structure having
- (a) wood frame walls,
  - (b) siding on said walls,

- (c) a roof frame on the walls with
  - (d) wood rafters which
  - (e) extend over the walls to form eaves,
  - (f) a facia attached to the ends of the rafters, and
  - (g) a soffit;
- the improvement comprising:
- (h) a composite block attached to each rafter having
- (i) a horizontal soffit support,
  - (ii) a vertical wall member,
  - (iii) first scabs on each side of the block attaching the soffit support to the wall member and the block to the eave portion of said rafter, and
  - (iv) second scabs on each side of the block attaching the soffit support to the eave portion of said rafter; and
  - (j) said soffit attached to the underside of the soffit support.
8. A composite block adapted to form a cornice on a brick veneered, wood framed building comprising:
- (a) a horizontal soffit support,
  - (b) a vertical wall member,
  - (c) first scabs on each side of the block attaching the soffit support to the wall members,
  - (d) second scabs on each side of the block attached to the soffit support and adapted to attach the soffit support to the eave portion of rafters,
  - (e) third scabs on each side of the block attached to the wall member adapted to attach the wall member to the eave portion of a rafter,
  - (f) a notch in the vertical wall member adapted to be fitted over a stringer attached to a wall frame,
  - (g) the underside of the soffit support adapted to have a soffit attached thereto, and
  - (h) a face of the vertical wall member adapted to have a facer board attached thereto.
